UNITED STATES PATENT OFFICE.

PETER KAISER, OF CROWN POINT, INDIANA, ASSIGNOR OF SIXTY-FIVE ONE-HUNDREDTHS TO CLAYTON D. ROOT, OF CROWN POINT, INDIANA.

HEAT-CONTROLLING MECHANISM FOR INCUBATORS, &c.

1,190,420.

Specification of Letters Patent.

Patented July 11, 1916.

Application filed March 15, 1916. Serial No. 34,286.

To all whom it may concern:

Be it known that I, PETER KAISER, a citizen of the United States, and a resident of Crown Point, in the county of Lake and 5 State of Indiana, have invented certain new and useful Improvements in Heat-Controlling Mechanism for Incubators, &c., of which the following is a full, clear, and exact specification.

10 My invention is concerned with incubators, brooders, etc., and it is designed to produce heat-controlling mechanism for the same in which the thermostat connections and devices by which the temperature of 15 the heating fluid is kept uniform shall be of the simplest possible nature, and hence very durable and not liable to get out of order.

To illustrate my invention, I have annexed hereto a sheet of drawings, in which 20 the same reference characters are used to designate identical parts in all the figures, of which,—

Figure 1 is a side elevation of a portion 25 of an incubator having my invention applied thereto, as seen in section on the line 1—1 of Fig. 2; Fig. 2 is a side elevation of the same, with the incubator seen as in section on the line 2—2 of Fig. 1; and Fig. 3 is a top plan view as seen in section on the 30 line 3—3 of Fig. 1, but with the boiler removed.

In carrying out my invention in its preferred form, as applied to an incubator, I employ the customary hollow casing 10, in 35 which is mounted the egg tray 11, and which is provided with the preferably removable cover or top 12. The casing may be of any desired construction, and is suitably supported, as by the legs 13.

40 In the upper portion of the casing, where my invention is to be employed in connection with an incubator of the hot-water circulating type, I place a pair of pipes 15 and 15^a, which follow the outline of the horizontal cross-section of the incubator near its 45 walls, each of said pipes being connected at one end with the horizontal supply tube 16, and at the other end to the horizontal discharge tube 17 located below the same.

50 These tubes 16 and 17 pass through a suitable aperture in the adjacent wall of the casing and are connected to the boiler 18, which has a plurality of vertical tubes 19 extending therethrough, so that the heat 55 from the lamp can pass upward through

said tubes and heat the water in the boiler 18. The lamp 20 is of any desired construction, and is preferably supported from the bracket 21 secured on the bottom of the casing, and is provided with the chimney 22, 60 which is preferably of metal, and has a transparent portion 23 through which the height of the flame may be observed for regulating the same. Secured on the side of the casing is a bracket 24, which has a lower 65 horizontal portion 25, which has projecting upwardly therefrom a short collar 26, which is preferably substantially square in horizontal cross section. When the lamp 20 is properly placed on the bracket, the top of 70 the chimney 22 extends slightly upward into the opening formed by the bottom of the collar 26. Pivoted at the upper edge, preferably to one side of the center of the collar, as by the rod 27, is a swinging flue 75 28, which is preferably rectangular in cross section, and tapers slightly from the bottom to the top, the bottom fitting over the top of the collar 26 with sufficient play so that it is free to turn from the full-line to the 80 dotted-line position shown in Fig. 1. Secured on the horizontal flange 29, projecting outwardly from the top of the bracket 24, is the seat 30 for the boiler 18, which seat preferably takes the form of a hollow, 85 rectangular, inverted, truncated cone, formed with a flange 31 on the right-hand side thereof, which serves as a stop for the flue 28 when it is in its vertical position, in which the heat from the lamp is all directed up through the tubes 19 of the boiler 18. Associated with this seat 30, I preferably employ a passage 32, which is adapted to coöperate with the flue 28 when it is 90 swung to the dotted-line position, in which a stop surface, preferably consisting of the left-hand side of the top of the flue 28, engages with the flange 34 projecting downward from the bottom of the passage 32 and limits the movement of the flue in that 95 direction. The seat 30 and the portion 25 of the bracket 24 are preferably connected by the brace rod 33.

The movement of the flue is controlled by the thermostat disks 35, which are supported on the bracket 36 secured on the interior of the casing 10 above the egg tray. Pivoted on the vertical arm 37 of the bracket 36 is a lever 38 of the third class, which preferably rests on the top of the thermo 100 105 110

stat disks 35. The outer end of this lever 38 projects through the vertical slot 41 in the casing, and has extending through an aperture in its outer end the link 42, the 5 effective length of which is controlled by the set nut 43 screwed on the upper end thereof, which preferably has an annular groove coöperating with the aperture in the end of the lever 38, so that the lever is adjusted and held simply by turning the nut 43. The lower end of the link 42 is pivoted to the bracket 44 secured to the adjacent side of the flue 28, and a weight 45 to 10 counterbalance the weight of the flue 28 is preferably held by a bend in the link 42.

The operation of the device will be readily apparent. Assuming that the apparatus is being started up with the temperature below the 103° for which it is set, the flue 20 28 will be in the full-line position shown, and the lever 38 will not tend to tilt it. When the temperature passes the 103° mark, the expansion of the thermostat disks 35 will cause them to raise the overlying lever, 25 and thus lift the outer end of the lever 38, raising the link 42, and tilting the flue 28, say to the dotted-line position shown in Fig. 1, in which all the heat from the lamp is deflected away from the boiler 18, and 30 the temperature of the circulating water is allowed to fall. When the temperature of the interior of the casing falls below the 103°, the lever 38 falls, and the weight 45 tilts the flue 28 back to the vertical full-line position.

While I have shown and described my invention as embodied in the form which I at present consider best adapted to carry out its purposes, it will be understood that 40 it is capable of modifications, and that I do not desire to be limited in the interpretation of the following claims except as may be necessitated by the state of the prior art.

I am aware of the prior patents to Foster, 45 No. 595,381, and Leas *et al.*, No. 1,085,273, and do not claim the structures therein shown and described.

What I do claim as new, and desire to 50 secure by Letters Patent of the United States, is:

1. In a device of the class described, the combination with a casing having heat-distributing appliances therein and a thermostat element fixedly supported therein, of a lamp supported outside of the casing, a stationary chimney on the lamp, surrounding the burner, a stationary collar supported from the casing having the chimney opening into its bottom, a swinging flue pivoted 55 near the top of the collar and overlapping the same to make a joint in all positions, a heat-applying member above the swinging flue having heat-utilizing passages extending therethrough, and link and lever connections from the thermostat element to the 60

swinging flue so that the expansion of the thermostat under undue heat will swing the flue so as to deflect some of the heat from the heat-utilizing passages.

2. In a device of the class described, the combination with a casing having heat-distributing appliances therein and a thermostat element fixedly supported therein, of a lamp supported outside of the casing, a stationary chimney on the lamp surrounding its burner, a stationary collar supported from the casing having the chimney opening into its bottom, a swinging flue pivoted near the top of the collar and overlapping the same to make a joint in all positions, a heat-applying member above the flue having heat-utilizing passages extending therethrough, a bracket support for the thermostat element within the casing, a single lever fulcrumed on the bracket and coöperating with the free side of the thermostat element and having its load arm extending outside of the casing, and a link extending from the load arm and connected to the flue to one side of its fulcrum.

3. In a device of the class described, the combination with a casing having heat-distributing appliances therein and a thermostat element fixedly supported therein, of a lamp supported outside of the casing, a stationary chimney on the lamp surrounding its burner, a stationary collar supported from the casing having the chimney opening into its bottom, a swinging flue pivoted near the top of the collar and overlapping the same to make a joint in all positions, a heat-applying member above the flue having heat-utilizing passages extending therethrough, a bracket support for the thermostat element within the casing, a single lever fulcrumed on the bracket and coöperating with the free side of the thermostat element and having its load arm extending outside of the casing, a link extending from the load arm and connected to the flue to one side of its fulcrum, and a counterbalance weight for the flue tending to hold it in its heating position.

4. In a device of the class described, the combination with a casing having heat-distributing appliances therein and a thermostat element fixedly supported therein, of a lamp supported outside of the casing, a stationary chimney on the lamp surrounding its burner, a stationary collar supported from the casing having the chimney opening into its bottom, a swinging flue pivoted near the top of the collar and overlapping the same to make a joint in all positions, a heat-applying member above the flue having heat-utilizing passages extending therethrough, a bracket support for the thermostat element within the casing, a single lever fulcrumed on the bracket and resting on the free side of the thermostat element and having its

load arm extending outside of the casing, a link connecting the lever and flue, a counter-balance weight on the link, and means for adjusting the effective length of the link,
5 consisting of a nut threaded on the upper end thereof and held to turn in the outer end of the lever through which it passes.

In witness whereof, I have hereunto set my hand and affixed my seal this 3rd day of March A. D. 1916.

PETER KAISER. [L. S.]
